ATTORNEY

UNITED STATES PATENT OFFICE.

FRED A. OBERHEU, OF DETROIT, MICHIGAN.

SIGN-SUPPORTING DEVICE.

Application filed November 8, 1924. Serial No. 748,654.

My invention relates broadly to the advertising art, and particularly to advertising schemes wherein signs or posters are supported from and upon the inner surface 5 of plate glass window panes; to thereby display the poster in a conspicuous position and in a manner such that the matter contained thereupon will be the more effectively and certainly brought to the attention of persons passing by the window.

Heretofore in supporting a poster for advertising purposes upon the inner surface of a window pane so that it will be seen from without the usual practice has been to 15 place the poster in place and then, while holding it against the window with one hand, place gummed labels or stickers about the sign overlapping its periphery and adhering thereto, and to the window glass. This 20 practice, however, is difficult in execution and is liable to result in unevenness and wrinkles in the sign, as one hand has to be devoted mostly to the holding in place of the sign while the stickers are being applied with the other. In addition, the labels 25 or stickers employed, besides being weak along the edge of the sign, present an unsightly appearance; as they necessarily project beyond the periphery thereof and are 30 likely not to be chosen or arranged with reference to a pleasing, an effective and an artistic appearance of the sign regarded in its entirety. If in accordance with a less careful practice blotches of paste or glue are 35 placed about the edge of the poster, and the same pressed against the glass, the result is even less pleasing in appearance and effective as an advertising medium.

The object of my invention therefore is 40 to provide a scheme or plan for supporting a sign or poster upon the inside of a window wherein supporters are first fastened to the poster to be supported at but not extending beyond the periphery thereof through and by means of an adhesive coating upon one 45 surface of the supporter, and the supporters then attached to the glass through and by means of adhesive coatings upon the other surfaces thereof; these second mentioned surfaces being the only coated surfaces exposed to persons outside the window when the sign is in place. This method leaves 50 both hands of the operator more free to ad-

just the sign and fasten it in place than in prior schemes; and, furthermore, provides 55 for the supporting of the sign in a way such that no parts of the supporting members made use of extends beyond the periphery thereof.

The supporting members made use of 60 therefore lay wholly inside the periphery of the sign or poster supported, and are seen throughout their entire areas by persons outside the window; and said members may therefore be so designed, formed and ar- 65 ranged as to be in harmony with, and to blend with and in various ways enhance the general appearance and the effectiveness of the poster as an advertising device. As an example of the thus carrying forward of the 70 broader sign supporting ideas of my invention, I have illustrated embodiments thereof wherein the supporter includes a pointer in the form, for example, of a hand or an arrow head arranged to point toward the main 75 central portion of the sign or poster, to thereby direct the attention of an observer to whatever may be impressed upon the sign. The supporters thus blend with the sign and form in effect a part thereof; and they may 80 obviously be made in various forms and colors, and otherwise adapted to the sign with which they are to be used to thereby better serve the purpose for which they are 85 designed.

The drawing accompanying and forming 90 a part of this application illustrates the preferred embodiment of my invention in several forms differing somewhat from one another and, referring thereto and to the reference numerals associated with the various figures thereof,

Figure 1 is a view showing a conventional 95 sign or poster attached to a window glass by four supporters made in accordance with my invention,

Figure 2 is a view showing the same end attained by the use of supporting members of another form,

Figure 3 is a view showing the supporter 100 at the upper right hand corner of Figure 1 by itself and somewhat larger than in Figure 1, and turned over so as to show the surface thereof which is next to the sign and which is therefore not visible in Figure 1,

Figure 4 is a view showing a form of sup-

porter which may be used intermediate the corners of a sign which is too large to be properly supported by four supporting members.

Referring now to the drawing, the reference numeral 5 designates a portion of a plate or other glass window pane such as is commonly used in store fronts, and 6 a poster or sign supported by and overlying the inside surface of the glass, so as to be visible from outside of the window. Obviously the sign may have any desired information or advertising matter written, printed or otherwise impressed thereupon.

15 The sign 6 is shown as rectangular, and as supported by four supporting members (called "supporters" in the concluding claims) each designated as a whole by the numeral 7; said members being made from 20 thin sheet material such, for example, as paper or cloth, or from laminated or other sheet material suitable for the purpose.

The surfaces of the supporters which are to contact with the poster are coated with an 25 adhesive material, as indicated by the surface shading in Figure 3, such coating extending preferably throughout the entire areas of the supporters. Said supporters are stuck to the sign as a preliminary step 30 in arranging for the support thereof from the glass; although it will be appreciated that the films of adhesive material between the supporters and the sign are concealed by the supporters, and are invisible from 35 outside the window.

The other surfaces of the supporters 7, that is the surfaces which appear in Figures 1 and 2 and which are visible from outside the window, also have adhesive coating material upon them so that they may be stuck 40 to the glass, and the sign supported therefrom through and by means of said supporting members. This last mentioned adhesive material is preferably localized at the outer 45 ends of the supporting members, as indicated by the surface shading at said outer ends; this being done in order to avoid as much as possible the reflection of light and consequent glare (as seen from outside the 50 window) by and due to the thin films of adhesive between the glass and the visible surfaces of the supporters. The coated portions of the supporters are preferably no greater in area than is necessary to provide 55 for the secure and certain support of the sign in order to minimize reflection effects and a certain degree of unsightliness at the joints between the supports and the glass, and in order that their uncoated exposed 60 areas may present a better appearance and may the better blend with the sign which they serve to support.

The supporting members as hereinbefore explained are each made up of two parts 65 one of which provides for the support of the

sign from the glass, and the other of which blends with and in a sense forms a part of the sign. Thus in Figure 1 each member 7 comprises an outer attaching portion 8 and an inner pointer portion 9 shown as in the 70 form of a hand with the first finger extended; while in Figure 2 the supporters are made up of outer portions 10 and inner arrow head portions 11. In both cases the pointer portions are arranged so as to point 75 toward the central portion of the sign which they support to thereby concentrate the attention of an observer upon the printed or other matter upon the sign.

The adhesive coating material upon the 80 surfaces of the supporting members which are visible from outside the window is preferably localized upon the attaching portions of said members, as indicated by surface shading, the pointer portions being uncoated; while the coating upon the surfaces 85 of said members which contact with the sign may extend throughout their entire areas. This plan provides stronger joints between the supporters and the sign supported; and there can be no reflection of light and consequent glare from these comparatively large 90 films of adhesive material between the sign and the supporting members as said areas are hidden by the said members.

The form of supporting member illustrated in Figure 4 is one which may be preferred in case support is required at one or more points between the corners of the sign. This form differs from the other hand form 100 only in that the outer attaching portion 12 is square, instead of triangular, thereby conforming more closely with the side edge of the sign and providing a somewhat larger exposed coated area in a supporting member 105 having substantially the same over all dimensions as the form with a triangular attaching portion.

Having thus described and explained my invention, I claim and desire to secure by 110 Letters Patent:

1. In combination, a poster or sign to be supported upon the inner side of a window pane, and a plurality of supporters each comprising a single thickness of thin sheet material spaced about and arranged within the periphery of the sign; the surfaces of said supporters next to the sign being stuck to the sign by an adhesive material, and each supporter comprising an attaching portion and a pointer portion extending therefrom toward the central portion of the sign; the exposed surfaces of the attaching portions of said supporters having adhesive coatings whereby they may be stuck to the window pane, to thereby support the sign, and the exposed surfaces of the pointer portions aforesaid having no coating of adhesive material upon them.

2. A supporter for supporting a sign or

poster from a window pane, the same being made from a single thickness of thin sheet material and comprising an attaching portion and a pointer portion; one surface of

⁵ said supporter having an adhesive coating thereupon so that it may be stuck to a sign or poster to be supported, and the other surface having an adhesive coating upon the

attaching portion thereof so that it may be stuck to a window pane; said other surface, ¹⁰ however, having no adhesive coating upon the pointer portion of the supporter.

Signed at Detroit, Michigan, this 27th day of October, 1924.

FRED A. OBERHEU.
